UNITED STATES PATENT OFFICE

93,894

DESIGN FOR A GARMENT HOOK

Fred J. Skinner, Springfield, Mass.

Application August 13, 1934, Serial No. 52,935

Term of patent 7 years

To all whom it may concern:—

Be it known that I, FRED J. SKINNER, a citizen of the United States of America, residing at Springfield, in the county of Hampden and State of Massachusetts, have invented a new, original, and ornamental Design for a Garment Hook, of which the following is a specification, reference being had to the accompanying drawing, forming a part thereof.

Fig. 1 is a top plan view with the hook open, as shown in Fig. 3.

Fig. 2 is a front elevational view of Fig. 1.

Fig. 3 is a side elevational view with the hook open, and

Fig. 4 is a side elevational view, with the hook in closed position.

I claim:—

The ornamental design for a garment hook, as shown and described.

FRED J. SKINNER.
